CLAIM

The ornamental design for a cleaning cup for coffee machine, as shown and described.

DESCRIPTION

FIG. 1 is a top perspective view of a cleaning cup for coffee machine, showing my new design;

FIG. 2 is a bottom perspective view thereof;

FIG. 3 is top perspective view thereof, in an open state;

FIG. 4 is a bottom perspective exploded view thereof;

FIG. 5 is a front view thereof;

FIG. 6 is a rear view thereof;

FIG. 7 is a left side view thereof;

FIG. 8 is a right side view thereof;

FIG. 9 is a top view thereof;

FIG. 10 is a bottom view thereof;

FIG. 11 is an enlarged detail view of area 11 in FIG. 1;

FIG. 12 is an enlarged detail view of area 12 in FIG. 3;

FIG. 13 is an enlarged detail view of area 13 in FIG. 3;

FIG. 14 is an enlarged detail view of area 14 in FIG. 9; and,

FIG. 15 is an enlarged detail view of area 15 in FIG. 9.

The broken lines in the drawings illustrate the portions of the cleaning cup for coffee machine, which form no part of the claimed design.

The dash-dot-dash broken lines encircling the enlarged views are for annotative purposes only and form no part of the claim thereof.

1 Claim, 15 Drawing Sheets
